UNITED STATES PATENT OFFICE.

ARTHUR KITSON, OF PHILADELPHIA, PENNSYLVANIA, ASSIGNOR TO THE KITSON HYDROCARBON HEATING AND INCANDESCENT LIGHTING COMPANY, OF SAME PLACE AND CHARLESTON, WEST VIRGINIA.

VAPOR-BURNING APPARATUS.

SPECIFICATION forming part of Letters Patent No. 665,112, dated January 1, 1901.

Application filed March 19, 1900. Serial No. 9,133. (No model.)

To all whom it may concern:

Be it known that I, ARTHUR KITSON, a subject of the Queen of Great Britain, and a resident of Philadelphia, (Germantown,) county 5 of Philadelphia, State of Pennsylvania, have invented certain new and useful Improvements in Vapor-Burning Apparatus, of which the following is a specification.

My invention relates to an apparatus burning the vapor of fluid hydrocarbons to produce light or heat; and more specifically it consists of an improved form of vapor-burning apparatus designed to consume unrefined petroleum or crude oil. The difficulties which 10 have heretofore prevented the commercial use of crude oil in this form of apparatus have been mainly due to the fact that such crude oil contains tar and a variety of other impurities which deposit in the vaporizing-chamber, clog the vapor-discharge outlet and other parts of the lamp apparatus, and thus extinguish the flame within a short period of time after the lamp has been started into operation.

I have discovered that by the use of a suitable filtering and preheating apparatus or by the introduction of a separating-chamber in the fuel-supply connections, or by the use of both these features of construction together, it is possible to construct an apparatus which 25 will burn crude oil as it comes from the well for a length of time at least equal to one night without the collection of impurities sufficient to clog the vaporizing apparatus to a degree which will prevent the normal operation of the apparatus as a whole.

The preferred form of apparatus embodying my invention is illustrated in the accompanying two sheets of drawings, in which—

Figure 1 is a vertical central section of an 30 incandescent vapor-burning lamp to which my invention has been applied. Fig. 2 is a horizontal section on line $s^1 s^2$ of Fig. 1 looking downward. Fig. 3 is an enlarged detail central section of the vaporizing-tube.

Throughout the drawings like reference-figures indicate like parts.

The lamp shown in Fig. 1 has an inclosing casing formed of the annular frame or reflector 1, the hemispherical glass globe 2, sus-

pended beneath the same, and the chimney 50 3, surmounting the same. Within the casing thus formed are one or more vapor-burners 44, preferably surmounted with incandescent mantles 55. These burners are mounted on a mixing-tube 6, to which the jet of vapor is 55 injected from the vaporizing-tube 7 through the discharge-orifice 8, located over the mouth of the mixing-tube. The vaporizing-tube 7 is inclined to the horizontal plane, as shown, having its discharge-orifice in the higher end 60 8 and the fuel-supply inlet at the lower end 9.

The oil or other fluid hydrocarbon is supplied through the tube 10, and in the line of the supply connections I insert a separating-chamber 11. Preferably this separating- 65 chamber is located on a level below the inlet end 9 of the vaporizing-tube. I prefer also to make the separating-chamber cylindrical in form, with its axis vertical, and to have the fuel-inlet to said separating-chamber tangential to the circumference thereof, as shown at 70 12 in Figs. 1 and 2, while the outlet connection from the separating-chamber to the vaporizing-tube is at 13, extending from the upper central portion of the separating-chamber. Any convenient connection may be employed; but preferably the vaporizing-tube 75 has a threaded extension 9^a in line with the oppositely-threaded extension 13 from the separating-chamber, and the threaded union 80 14 is employed to couple the two together. A discharge-tube 15 may be connected to the lower portion of the separating-chamber 11 and extended out through the surrounding lamp-casing in any convenient manner, as by 85 passing it through the washer 24, let into an opening in the glass globe 2. This discharge-tube 15 may be provided with a valve 16, preferably outside of the casing, or it may discharge into a larger receptacle. (Not shown.) 90

While the use of the separating-chamber alone may suffice to free the oil from the tar and other impurities, I prefer to also employ a preheating and filtering device in the line of the oil connections to the separating-chamber. Such apparatus may comprise a filter-tube 17, also inclined slightly to the horizontal plane, having the oil-inlet at its upper 95

end 22, while its lower end 21 is connected by the tube 20 to the separating-chamber. This preheating-tube 17 is preferably given a filtering action also by filling it with a quantity of finely-divided material 18, confined between the wire-gauzes 19 19, located at either end of the tube. I preferably employ also a heat-shield 23 just above the vaporizing-tube and between it and the tube 17. In the vaporizing-tube I may employ a thermostatically-operated valve 25 to automatically control the admission of oil and vapor to the vaporizing-tube.

The method of operation of my invention is as follows: The crude-oil supply through the tube 10 is heated to a considerable degree and partially vaporized in the tube 17 and is also filtered in passing through the material 18 therein, so as to give up a considerable portion of its solid impurities and free carbon. The tar contained therein separates out as a liquid by specific gravity and drains down through the pipe 20 to the separating-chamber 11. The partially-vaporized oil also passes down through said tube 20, and the whole entering the separating-chamber through the tangential discharge-pipe 12 is caused to circulate about the separating-chamber. The tar and other impurities of greater specific gravity will be thrown off to the circumference and drained down into the bottom of the separating-chamber and through the discharge-tube 15. The oil and vapor being lighter will be forced to the center and pass up through the connection 13 to the lower end of the vaporizing-tube 7, where the complete vaporization of the oil and super-heating of the vapor will be accomplished and the vapor discharged through the orifice 8 down into the mixing-tube 6 in the well-known way. The tar depositing in the vaporizing-tube 7 will also drain back into the separating-chamber 11. At proper intervals the filtering material 18 may be removed from the tube 17 and clean material substituted, and the accumulation of tar in the separating-chamber may be drawn off through the discharge-tube 15.

The advantages of my invention comprise principally the feature of complete drainage of the preheating, filtering, and vaporizing system into one separating-chamber and also the effective separation of the oil and vapor from the heavier impurities by centrifugal action in said separating-chamber. These features of the invention enable me to use crude oil, which costs two or three cents a gallon, and effect the saving of three-fourths of the full cost which the use of refined kerosene-oil would entail. I find that lamps equipped with my invention will burn continuously for at least one night's time on crude oil without attention. The tar and other materials eliminated from the oil are also of commercial value when collected in quantities. The location of the separating-chamber and the connecting-tube 20 within the lamp-cas-

ing keeps them in a highly-heated condition and prevents the partial condensation of the vapor and the cooling of the heated oil which would result if they were located outside of the lamp-casing. The employment of flexible tubes and the arrangement of threaded connections shown also make the assembling of the parts of the apparatus or their removal extremely simple and convenient.

It is evident, of course, that various changes could be made in the details of construction illustrated without departing from the spirit and scope of my invention so long as the relative arrangement of parts or the principle of operation disclosed is preserved. Other forms of separating-chamber and connections might be substituted, and the filtering preheating-chamber might be of different form or might be dispensed with entirely. The connections might be varied and other arrangements of piping and valves substituted; but all such modifications I should still consider within the boundaries of my invention.

Having, therefore, described my invention, what I claim as new, and desire to protect by Letters Patent, is—

1. The combination in a vapor-burning apparatus of the mixing-tube, the oil-supply connection, a vapor-burner, and the vaporizing-tube inclined slightly to the horizontal plane and having the discharge-opening in the higher end over the mouth of the mixing-tube, together with the filter in the line of the oil connections located over the vapor-burner.

2. The combination in a vapor-burning apparatus of the mixing-tube, the oil-supply connection, a vapor-burner, and the vaporizing-tube inclined slightly to the horizontal plane and having the discharge-opening in the higher end over the mouth of the mixing-tube, together with the filter in the line of the oil connections also located over the vapor-burner, said filter comprising a tube also inclined to the horizontal plane and having the oil-inlet at its higher end.

3. The combination of the vapor-burning lamp and chimney therefor, the vaporizing-tube and the filter extending across the lamp-chimney, both inclined to the horizontal plane, and the tube connecting the lower portions of the vaporizing-tube and filter, located within said chimney.

4. The combination in a vapor-burning apparatus of the mixing-tube, the oil-supply connection, a vapor-burner, and the vaporizing-tube inclined slightly to the horizontal plane and having the discharge-opening in the higher end over the mouth of the mixing-tube, together with the separating-chamber located in the line of the oil-supply connections.

5. The combination in a vapor-burning apparatus of the mixing-tube, the oil-supply connection, a vapor-burner, and the vaporizing-tube inclined slightly to the horizontal plane and having the discharge-opening in the higher end over the mouth of the mixing-

- tube, together with the separating-chamber located in the line of the oil-supply connections, and the valve-controlled outlet from said separating-chamber.
- 5 6. The combination in a vapor-burning apparatus of the mixing-tube, the oil-supply connection, a vapor-burner, and the vaporizing-tube inclined slightly to the horizontal plane and having the discharge-opening in the higher end over the mouth of the mixing-tube, together with the separating-chamber located in the line of the oil-supply connections, and below the oil-inlet to the vaporizing-tube.
- 10 7. The combination in a vapor-burning apparatus of the mixing-tube, the oil-supply connection, a vapor-burner, and the vaporizing-tube inclined slightly to the horizontal plane and having the discharge-opening in the higher end over the mouth of the mixing-tube, together with the separating-chamber located in the line of the oil-supply connections and below the oil-inlet to the vaporizing-tube, and the valve-controlled outlet from the bottom of said separating-chamber.
- 15 8. The combination in a vapor-burning apparatus of the mixing-tube, the oil-supply connection, a vapor-burner, and the vaporizing-tube inclined slightly to the horizontal plane and having the discharge-opening in the higher end over the mouth of the mixing-tube, together with the filter in the line of the oil connections also located over the vapor-burner, and the separating-chamber in the line of connections from the filter to the vaporizing-tube.
- 20 9. The combination in a vapor-burning apparatus of the mixing-tube, the oil-supply connection, a vapor-burner, and the vaporizing-tube inclined slightly to the horizontal plane and having the discharge-opening in the higher end over the mouth of the mixing-tube, together with the filter in the line of the oil connections also located over the vapor-burner, said filter comprising a tube also inclined to the horizontal plane and having the oil-inlet at its higher end, and the separating-chamber in the line of connections from the filter to the vaporizing-tube.
- 25 10. The combination in a vapor-burning apparatus of the mixing-tube, the oil-supply connection, a vapor-burner, and the vaporizing-tube inclined slightly to the horizontal plane and having the discharge-opening in the higher end over the mouth of the mixing-tube, together with the filter in the line of the oil connections also located over the vapor-burner, said filter comprising a tube also inclined to the horizontal plane and having the oil-inlet at its higher end, and the separating-chamber in the line of connections from the filter to the vaporizing-tube, said separating-chamber being located below the level of the inlet to the vaporizing-tube.
- 30 11. The combination in a vapor-burning apparatus of the mixing-tube, the oil-supply connection, a vapor-burner, and the vaporizing-tube inclined slightly to the horizontal plane and having the discharge-opening in the higher end over the mouth of the mixing-tube, together with the filter in the line of the oil connections also located over the vapor-burner, said filter comprising a tube also inclined to the horizontal plane and having the oil-inlet at its higher end, and the separating-chamber in the line of connections from the filter to the vaporizing-tube, said separating-chamber being located below the level of the inlet to the vaporizing-tube, together with the inclosing casing surrounding the vapor-burner and the separating-chamber.
- 35 12. The combination of the vapor-burning lamp and chimney therefor, the vaporizing-tube, and the filter extending across the lamp-chimney, both inclined to the horizontal plane, and the tube connecting the lower portions of the vaporizing-tube and filter located within said chimney, the globe and casing below said chimney together forming an inclosing casing within which the vapor-burning apparatus is located, and the separating-chamber in the line of connections from filter to vaporizing-tube also located within said inclosing casing.
- 40 13. The combination of the vapor-burning lamp and chimney therefor, the vaporizing-tube and the filter extending across the lamp-chimney, both inclined to the horizontal plane, and the tube connecting the lower portions of the vaporizing-tube and filter, located within said chimney, the globe, and casing below said chimney together forming an inclosing casing within which the vapor-burning apparatus is located, and the separating-chamber in the line of connections from filter to vaporizing-tube also located within said inclosing casing, together with the discharge-tube extending from the lower part of the separating-chamber through the inclosing casing and provided with a valve outside said casing.
- 45 14. The combination of the vapor-burner, the vaporizing-tube in the heating zone of the burner, the heating-chamber, also in the heating zone of the burner and the separating-chamber located in the line of connections between the heating-chamber and the vaporizing-tube, said separating-chamber being cylindrical in form with its axis vertical and having its inlet from the heating-chamber discharging in a tangential, horizontal direction while its outlet to the vaporizing-tube connects with its upper central portion.

Signed at New York, N. Y., this 27th day of February, 1900.

ARTHUR KITSON.
